DATA TRANSMITTER HOUSING OR SIMILAR ARTICLE

Eliot F. Noyes, New Canaan, Conn., and Rae F. Tankard,
Johnson City, N.Y., assignors to International Business
Machines Corporation, New York, N.Y., a corporation
of New York

Filed Mar. 23, 1960, Ser. No. 59,850

Term of patent 14 years

(Cl. D26—5)

FIG. 1

FIG. 2

FIG. 3

FIG. 4

Fig. 1 is a front perspective view of a data transmitter housing or similar article showing our new design.

Fig. 2 is a rear perspective view of the same.

Fig. 3 is a top plan view of the same.

Fig. 4 is a right side elevational view of the same.

We claim:

The ornamental design for a data transmitter housing or similar article, as shown.
